CLAIM

The ornamental design for a tennis ball launch bag, as shown and described.

DESCRIPTION

1. Tennis ball launch bag

FIG. 1.1 is a perspective view of a tennis ball launch bag, showing my new design;

FIG. 1.2 is a first side elevation view thereof;

FIG. 1.3 is a second side elevation view thereof;

FIG. 1.4 is a rear side elevation view thereof;

FIG. 1.5 is front side elevation view thereof;

FIG. 1.6 is a top plan view thereof;

FIG. 1.7 is a bottom plan view thereof; and

FIG. 1.8 is a perspective view showing in condition of usage.

The word "SLINGER" forms no part of the claimed design.
